US00D861639S

(12) **United States Design Patent** (10) Patent No.: **US D861,639 S**
(45) Date of Patent: **** Oct. 1, 2019**

(54) **WIRELESS SPEAKER**

- (71) Applicant: **Broan-NuTone LLC**, Hartford, WI (US)
- (72) Inventors: **Benjamin Thorpe Puffer**, Hartford, WI (US); **Kenneth John Jonas**, Mequon, WI (US)
- (73) Assignee: **Broan-NuTone LLC**, Hartford, WI (US)
- (**) Term: **15 Years**
- (21) Appl. No.: **29/587,244**
- (22) Filed: **Dec. 12, 2016**

Primary Examiner — Keli L Hill*(74) Attorney, Agent, or Firm* — Barnes & Thornburg LLP**CLAIM**

The ornamental design for a wireless speaker, as shown and described.

DESCRIPTION

FIG. 1 is a front side perspective view of a wireless speaker, embodying our new design.

FIG. 2 is a front plan view thereof.

FIG. 3 is a back plan view thereof.

FIG. 4 is a top plan view thereof.

FIG. 5 is a bottom plan view thereof; and,

FIG. 6 is a side elevation view thereof, the left and right sides being mirror images of one another.

The broken lines depict environmental subject matter only and form no part of the claimed design.

1 Claim, 3 Drawing Sheets

See application file for complete search history.
